(57) **CLAIM**

The ornamental design for a modular speed reducer as shown and described.

DESCRIPTION

FIG. 1 is a perspective view of a modular speed reducer showing my new design;

FIG. 2 is a top view thereof;

FIG. 3 is a front view thereof;

FIG. 4 is a rear view thereof;

FIG. 5 is a right side view thereof;

FIG. 6 is a left side view thereof;

FIG. 7 is a perspective view thereof in a use context; and, FIG. 8 is a top view thereof in a use context.

The bottom view is omitted and forms no part of the claimed design.

The broken lines depict structure or features which form no part of the claimed design.
